(57) **CLAIM**

The ornamental design for an electronic device with animated graphical user interface as shown and described.

DESCRIPTION

FIG. 1 is a front view of an electronic device with animated graphical user interface showing a first image of the claimed design;

FIG. 2 is a second image thereof;

FIG. 3 is a third image thereof;

FIG. 4 is a fourth image thereof;

FIG. 5 is a fifth image thereof;

FIG. 6 is a front view of another embodiment of an electronic device with animated graphical user interface showing a first image of the claimed design;

FIG. 7 is a second image thereof;

FIG. 8 is a third image thereof;

FIG. 9 is a fourth image thereof; and

FIG. 10 is a fifth image thereof; and,

FIG. 11 is a front view of an alternate electronic device showing the animated graphical user interface of FIG. 1 applied thereto. The animated graphical user interface designs of FIGS. 2-5 and 6-10 may be similarly applied thereto.

The outer broken lines in the figures show an electronic device, or an alternate electronic device, and form no part of the claimed design. The other broken lines in the figures show portions of the animated graphical user interface that form no part of the claimed design.

The appearance of the animated image sequentially transitions between the images shown in FIGS. 1-5 and FIGS. 6-10, respectively. The process or period in which one image transitions to another forms no part of the claimed design.
